(57) **CLAIM**

The ornamental design for nozzle, as shown and described.

DESCRIPTION

FIG. 1 is a perspective view of the nozzle embodying the new design;
FIG. 2 is a top view thereof;

FIG. 3 is a left side view thereof, the right side view being a mirror image thereof;

FIG. 4 is a rear view thereof;

FIG. 5 is a front view thereof;

FIG. 6 is a perspective view of a first alternative embodiment of the nozzle;

FIG. 7 is a top view thereof;

FIG. 8 is a left side view thereof, the right side view being a mirror image thereof;

FIG. 9 is a rear view thereof;

FIG. 10 is a front view thereof;

FIG. 11 is a perspective view of a second alternative embodiment of the nozzle;

FIG. 12 is a top view thereof;

FIG. 13 is a left side view thereof, the right side view being a mirror image thereof;

FIG. 14 is a rear view thereof;

FIG. 15 is a front view thereof;

FIG. 16 is a perspective view of a third alternative embodiment of the nozzle;

FIG. 17 is a top view thereof;

FIG. 18 is a left side view thereof, the right side view being a mirror image thereof;

FIG. 19 is a rear view thereof; and,

FIG. 20 is a front view thereof.

FIGS. 1-20 show features of a nozzle in phantom lines. These features are shown for environmental purposes and do not form any part of the claimed design. The phantom lines immediately adjacent the solid-line portions of the design form the boundary of the design, with the phantom lines forming no part of the claimed design.
